BRANDING CHUTE FOR CATTLE

William A. Walker and Lloyd M. Hill,
Eliasville, Tex.

Application February 21, 1945, Serial No. 579,001

4 Claims. (Cl. 119—103)

1

This invention relates to a branding chute for cattle, and more particularly to such a device adapted to hold a calf or similar animal in position for operation thereupon, such as branding, castration, dehorning, or the like.

A primary object of this invention is the provision of an improved device adapted securely to hold a calf or similar animal, provided with means for securing the head of the animal in position and squeezing the sides of the same, and correspondingly provided with front and rear means for holding the animal against longitudinal movement through the chute.

An additional object of the invention is the provision of such device which may be readily tilted to its side in such manner that the calf may be readily positioned for operation thereupon.

A still further object of the invention is the provision of such device provided with a door in the squeeze side thereof, which may be opened, whereby ready access may be had to the flank of the animal for operation thereupon as desired.

Still another object of the invention resides in the provision of such device which will be sturdy and durable in construction, reliable and efficient in operation, and relatively simple and inexpensive to manufacture and assemble.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings—

Figure 1 is a side elevational view of one form of device embodying this inventive concept, certain concealed parts thereof being indicated in dotted lines.

Figure 2 is a front elevational view of the device disclosed in Figure 1 as viewed from the right side thereof, certain parts thereof being broken away;

Figure 3 is an enlarged detail view showing a portion of a cattle with its head clamped by the head holder of the invention;

Figure 4 is a sectional view taken substantially on the line 4—4 of Figure 3 and in the direction of the arrows;

Figure 5 is a rear end view of the device showing it in position for performing an operation on the cattle; and

Figure 6 is a fragmentary perspective view

2 showing a part of the horizontally slidable gate and its means for operation.

Similar reference characters refer to similar parts throughout the several views of the drawings.

Having reference now to the drawings there is generally indicated at 10 a base, to which is secured at each end as by means of bolts and nuts 11 a supporting plate 12 with an upturned extension. Secured, as by welding, to the opposite extremities of the supporting plate 12 and the extensions respectively, is a floor 12' and a side or gate 22 angularly disposed frame members 13, at opposite ends of the device from which extend transverse supporting members 14, terminating at the upper extremities of vertical uprights 15, are secured to the base 10. Horizontal transverse frame members 16 and 17, respectively, connect the upper and lower extremities of the uprights 15.

Extending in opposite angular relation, upwardly from the base 10 and oppositely inclined with respect to the angularly disposed supporting members 13 are posts 18 to guide the animal in entering and leaving the chute.

Pivoted in brackets 20 secured adjacent the upper extremities of the members 13, as by pivot pins 21, is the tiltable gate member 22, from the lower extremity of which extends a transverse supporting member or pitman 23 pivoted by pin 24, to which is hingedly secured as by means of pivot pins 24' an oppositely disposed squeeze side or gate 25. The pivot pins 24 and 24' consist of parts of the framing of the gates 22 and 25. The upper extremity of the member 25 has secured thereto as by means of pivot pin 26 a transversely extending bar 27, the lower surfaces of which is provided with ratchet teeth 28, adapted to engage a member 29 secured to the upper extremity of the side 22. A handle 30 extends outwardly from the upper extremity of the member 27.

The member 27 is biased downwardly, as by the spring 31 which is secured to the pivot point 32 of a transversely extending member 33, the extremity of which is secured in a clamp or bracket 34. The bracket 34 is secured to the side 25.

A head holder 36 is provided for securing the head of a calf by swinging about the vertical hinge pin 36'. The head holder 36 includes an arcuate member 37 terminating in sleeves 38 which are slidably mounted on horizontally extending rods 39, headed as at 40, and secured to an intermediate portion 41 of the hinge pin

36' (see Figure 3). A spring 41' is secured to one of the horizontal rods 39 and to a part of the framing of the gate or side 25 in order to yieldingly oppose the pivotal operation of the head holder 36. A horizontally slideable gate consisting of a plurality of bars 42 held assembled by the bracket 42' is positioned across the open extremity between the sides 22 and 25, being passed through suitable apertures in the brackets 44', which are fixed to the gate 25, as by the welds 25', and also through apertures 45' in the gate 22. The bracket 42' is provided with a handle 43 to permit withdrawal of the same when it is desired to release the animal. A latch 46' is pivoted to the side or gate 25 and overlies the bracket 42' to hold the gate, formed by the bars 42, releasably in place.

A chain 45 is secured at one extremity thereof to the arcuate member 37 of the head holding member 36, and has its opposite extremity suitably secured in the keeper 47 which is fixed to the side wall 22, to limit the movement of the member 37 on the rods 39. A second chain 48 is adapted to be secured at one extremity, as at 49, to the side wall 22, and releasably secured between lugs 50 mounted on the opposite extremity of the side wall 25.

A latch keeper 51 is pivotally secured as at 52 to an intermediate point of the side 22, being biased toward latching position by a spring 53, and is provided with a releasing handle 54 terminating in a right angularly disposed handle member 55 adjacent the upper extremity of the side 22.

From the foregoing the operation of the device should now be understandable. When the parts are placed in the position shown in Figure 1, and the gate bars 42 are closed, a calf is driven into the device from the open end. The side 25 is then moved inwardly about the hinge members 24, as best seen in Figure 2, by pulling inwardly the handle 30 until the animal is securely squeezed between the sides. The ratchet means 28 holds the sides 25 and 22 in the desired position. The head holding member 36 is then moved horizontally until the head of the animal is securely retained by the arcuate member 37 pressing the animal head against a part of the side 22. The chain 45 is then fastened in the keeper 47. The device is then tilted to its side, until the latch member 51 engages the transverse frame member 16, whereupon the animal is suitably held, the chain 48 precluding any rearward motion of the animal in position for branding or similar operation.

A door 60 positioned in the side wall 22 and hingedly mounted as on hinge pin 63 is adapted to be opened as by means of a handle 64 to provide ready access to the body of the animal for a suitable operation thereon.

From the foregoing it will now be seen that there is herein provided a device accomplishing all the objects of this invention and others including many advantages of great practical utility and commercial importance.

As many embodiments may be made of this inventive concept, and as many modifications may be made in the embodiments hereinbefore shown and described, it is to be understood that all matter herein is to be interpreted merely as illustrative and not in a limiting sense.

We claim:

1. A tilting chute for branding comprising a base, angularly inclined frame members secured to said base, a first side pivotally secured to one

of said frame members, a second side, a pitman connecting the lower portions of said sides, a rack gear having ratchet teeth pivoted to the second side and lockingly engaging the upper portion of said first side, a spring secured to said rack gear and said second side normally urging said rack gear to the latching position, a support secured to said base, a latch secured to said first side and cooperable with said support for maintaining both of said sides in a selected position, a slideable gate closing the sides at one pair of ends thereof, a chain releasably extending across the opposite ends of said sides.

2. A tilting chute for branding comprising a base, angularly inclined frame members secured to said base, a first side pivotally secured to one of said frame members, a second side, a pitman connecting the lower portions of said sides, a rack gear having ratchet teeth pivoted to the second side and lockingly engaging the upper portion of said first side, a spring secured to said rack gear and said second side normally urging said rack gear to the latching position, a support secured to said base, a latch secured to said first side and cooperable with said support for maintaining both of said sides in a horizontal position, a slideable gate closing the sides at one pair of ends thereof, a chain releasably extending across the opposite ends of said sides, substantially parallel rods pivotally secured to said second side, an arcuate head engaging bracket slidably secured to said rods, a chain secured to said head engaging bracket and said first bracket for limiting the sliding movement of said bracket on said parallel rods.

3. In a tilting chute for branding cattle, a base, a frame having portions angularly inclined to the base and secured to said base, a side pivotally mounted on one of the angular portions of said frame, a second side hingedly secured to a member which is pivoted to said first side adjacent the bottom thereof, ratchet means including a rack gear extending between the top of said sides to permit latching of said two sides at various positions with respect to each other, a slideable gate extending between said sides at one end thereof, a chain releasably extending across the opposite ends of said side, a head engaging bracket pivotally and extensibly secured to one of said sides, and means secured to the one of said sides and said bracket for varying the relative longitudinal position of said last mentioned bracket.

4. In a tilting chute for branding cattle, a base, a frame having portions angularly inclined relative to the base and secured to said base, a side pivotally mounted on one of said angularly inclined portions of said frame, a second side hingedly secured to a member which is pivoted to said first side adjacent the bottom thereof, ratchet means including a pivoted rack gear extending between the top of said sides to permit latching of said two sides at various positions with respect to each other, resilient means reacting on said rack gear for normally biasing said gear to the latching position, slideable gate means extending between said sides at one end thereof, a chain releasably extending across the opposite ends of said side, a head engaging bracket pivotally and extensibly secured to one of said sides, means secured to the one of said sides and said bracket for varying the relative longitudinal position of said last mentioned bracket, and latch means for holding said first side to said frame

when rotated about said pivot in a horizontal position with respect thereto.
